UNITED STATES PATENT OFFICE

FRED G. SHOEMAKER, OF SYRACUSE, NEW YORK

SPARK PLUG IGNITION TERMINAL

Application filed March 2, 1928. Serial No. 258,517.

This invention relates to spark plugs for internal combustion engines, but more particularly to the cable terminal connections therefor.

5 The invention has for its object to provide a locking device to lock the high tension cable terminal securely to but removably from the spark-plug terminal, to the end that the cable terminal, while being 10 readily removable from the spark-plug terminal, will not be casually displaced nor disconnected therefrom by vibration or accidental cause, and which cannot in any event be removed or disconnected from the 15 terminal on the spark-plug by longitudinal pull or strain on the ignition cable.

A further object of the invention is to provide a positive lock for the purpose recited, which does not restrict the flexibility 20 of the cable connection in any manner with respect to the spark-plug, and which embodies the essential features of lightness, cheapness, simplicity, safety and efficiency.

With these objects in view, the invention 25 consists of the novel construction of the terminal and lock, and in certain combinations of parts, all of which will be first fully described and afterwards specifically pointed out in the appended claims.

30 Referring to the accompanying drawing—

Figure 1 is a longitudinal sectional view of the type of terminal employed in connection with my improved locking device;

35 Figure 2 is a side elevation of the same;

Figure 3 is a front elevation of the locking device before its attachment to the terminal;

Figure 4 is a side elevation of the same;

40 Figure 5 is a front elevation of the assembled terminal and locking device; and

Figure 6 is a side elevation of the same.

Like numerals of reference indicate the same parts throughout the several figures, 45 in which—

1 indicates a spark-plug-cable terminal of conventional form, the same including the usual socket member 2 which receives the high tension cable (not shown), and the 50 forked terminal member 3. The fingers 4

of this forked member are provided with slightly flared ends 5 and concaved bosses 6, the concavities of said bosses being complemented and opposed as shown in Figure 1.

55 In each of the fingers 4 of the forked member 3 and in longitudinal plane with the center of the concaved bosses 6, I provide a hole or perforation 7.

8 indicates the locking device which, as shown in Figures 3 and 4, is constructed of wire, preferably music or other spring wire. Both ends of the locking device 8 terminate in opposed trunnions 9, and the body thereof incorporates two opposed coiled formations 10 intermediate the said trunnions 9 and the transverse central portion 11, which transverse central portion 11 is of greater length than the width of that portion of the structure immediately adjacent the said 70 trunnions 9. The effect of this construction is to impart to the two intermediate coiled formations 10 a considerable spring resilience within the limits defined by the full and dotted lines in Figure 3.

75 In assembling the device, the trunnions 9 are sprung outwardly and caused to enter the perforations 7 in the fingers 4 of the forked terminal member 3, and when thus positioned, the extreme ends 12 of the said 80 trunnions 9 are bent at right angles to the said trunnions, as shown in Figures 5 and 6, thereby permanently retaining the locking device 8 on the forked terminal member 3.

85 In operation the locking member 8 is raised into position shown in dotted lines in Figure 6, and the forked terminal member 3 is forced on to the spherical spark-plug terminal, which operation causes the two 90 fingers 4 of said forked terminal to straddle the said spherical spark-plug terminal, and to receive the latter within the opposed concaved bosses 6. When in this position, the locking member 8 is swung down into 95 position shown in full lines in Figure 6, which operation disposes the central transverse portion 11 of the locking member directly across the opening between the ends 5 of the forked terminal member, and clos- 100

ing said opening as shown in Figure 5. The locking member 8 in assuming this position, carries its opposed coiled formations over the extending bosses 6 of the fingers 4, said 5 coiled formations springing outwardly into position shown in dotted lines in Figure 3, in passing over said bosses, and again assuming their normal form when the locking member 8 has reached its operative locking 10 position shown in Figure 6, in which position each of the opposed bosses 6 is confined within the substantially circular space defined by the said opposed coiled formations 10.

15 This coaction between the locking member 8 and the terminal member 3, efficiently retains the said locking member in its effective locking position, and insures the efficient retention of the forked terminal 3 upon the 20 spherical spark-plug terminal, to the end that the former cannot be casually nor accidentally displaced or removed therefrom, nor in fact intentionally disconnected until the said locking member 8 is again swung 25 up into position shown in dotted lines in Figure 6.

Having thus fully described the invention, I do not wish to be understood as limiting myself to the exact construction shown and 30 described, but I consider myself clearly entitled to all such changes and modifications as fall within the limit and scope of the appended claims.

What I claim as new and desire to secure 35 by Letters Patent of the United States is—

1. In combination with a forked ignition-cable-terminal having two opposed projecting bosses and a pair of perforations in the fingers of said forked terminal, a locking 40 member including opposed trunnions to enter the said perforations in the forked terminal, a central transverse portion adapted to close the opening at the end of the forked terminal, and opposed coiled formations in 45 intermediate the said trunnions and the said central transverse portion, the said opposed coiled formations being adapted to engage the said opposed projecting bosses and to confine said opposed projecting bosses within 50 in the space defined by said opposed coiled formations.

2. In combination with a forked ignition-cable-terminal having two opposed projecting bosses and a pair of perforations in the 55 fingers of the said forked terminal, a locking member including opposed trunnions to enter the said perforations in the forked terminal, a central transverse portion adapted to close the opening at the end of the forked terminal, and also including opposed portions intermediate the said central transverse portion and the said trunnions for engagement with the said opposed projecting bosses to retain the said locking member in 60 effective operative position.

3. In combination with a forked ignition-cable-terminal, a locking member including means for effecting pivotal connection with the said terminal, a central transverse portion adapted to close the end of the said 70 forked terminal, and also including means for additional engagement with the said forked terminal to retain the said locking member in effective operative position.

4. The combination with a terminal connector for an electrical cable, said connector having a pair of yieldable jaws to receive a complementary member, of a locking member pivotally connected to be angularly movable on said connector and adapted to lock said 80 connector to said complementary member.

5. In combination with a cable provided with a forked terminal adapted to receive a complementary member of a U-shaped locking member having its legs pivotally connected to the legs of said forked terminal and movable relative thereto, so that its central transverse portion will gap the forks of said terminal.

6. In combination with a cable provided 90 with a snap fastener adapted to receive a complementary member of a locking member pivotally connected to, and angularly movable on, the terminal of said cable to lock said snap fastener to said complementary 95 member.

7. An electric terminal connector comprising a pair of clamping jaws spaced from each other at one of their extremities, a metal bail pivoted to said jaws to engage 100 their outer faces, said jaws being provided with recesses located at points between the pivot connections of the bail and the aforementioned extremities for engagement with a terminal, a portion of the bail being 105 adapted to be moved into engagement with the outer faces of said jaws adjacent said recesses, and cooperating means on said jaws and bail for yieldably securing said bail in predetermined position on said jaws.

In testimony whereof I affix my signature.

FRED G. SHOEMAKER.
